(57) **CLAIM**

We claim the ornamental design for a detection device for a fluid conduit or fluid dispensing device, as shown and described.

DESCRIPTION

FIG. 1 depicts an isometric view of a detection device for a fluid conduit or fluid dispensing device (hereinafter referred to as a “detection device”).

FIG. 2 depicts a front view of the detection device of FIG. 1.

FIG. 3 depicts a side view of the detection device of FIG. 1.

FIG. 4 depicts the other side view of the detection device of FIG. 1.

FIG. 5 depicts a back view of the detection device of FIG. 1.

FIG. 6 depicts a top view of the detection device of FIG. 1.

FIG. 7 depicts a bottom view of the detection device of FIG. 1; and,

FIG. 8 depicts an off-angle view of the detection device of FIG. 1.

The detection device for a fluid conduit or fluid dispensing device in the accompanying figures may be positioned on a fluid conduit, such as a pipe, or positioned on a fluid dispensing device, such as a fire hydrant or valve.

Broken lines are used to depict features or elements that are not considered to be part of the claimed design.

It is to be understood that many of the surface intersections in the depicted embodiments may intersect such that a blended or lightly-rounded edge is formed. As such, there may be no “hard” edge present at such locations. A virtual edge may nonetheless be defined at such locations, as represented by a “tangent line” or “tangent edge” which are depicted as grey, dash-dot-dot lines.
